UNITED STATES PATENT OFFICE.

NIELS MARTIN HANSEN, OF TOLEDO, OHIO, ASSIGNOR TO THE DE VILBISS MANUFACTURING COMPANY, OF TOLEDO, OHIO, A CORPORATION OF OHIO.

AIR-BRUSH.

1,016,143.

Specification of Letters Patent.

Patented Jan. 30, 1912.

Application filed November 3, 1910. Serial No. 590,536.

To all whom it may concern:

Be it known that I, NIELS MARTIN HANSEN, a citizen of the United States, and a resident of Toledo, in the county of Lucas and State of Ohio, have invented a certain new and useful Air-Brush; and I do hereby declare the following to be a full, clear, and exact description of the invention, such as will enable others skilled in the art to 10 which it appertains to make and use the same, reference being had to the accompanying drawings, and to the figures of reference marked thereon, which form a part of this specification.

15 My invention relates particularly to air-brushes; and has for its object to simplify and improve upon apparatus of this class, minimize the cost of construction thereof, and to attach the liquid receptacle and 20 handle for relative adjustment to suit the angle at which it is desired to hold the receptacle or the handle to render access to corners or the like.

Further objects of my invention, as well 25 as the operation, construction and arrangement of the parts thereof, are fully described in the following specification, and while the invention, in its broader aspect is capable of embodiment in numerous forms, 30 a preferred embodiment thereof is illustrated in the accompanying drawings, in which,—

Figure 1 is a side elevation of an apparatus embodying the invention, with portions broken away. Fig. 2 is a top plan view thereof with a part broken away, and Fig. 3 is a front elevation of the receptacle top and parts carried thereby, with the handle turned at an angle to the axis of the 40 top.

Referring to the drawings, 1 designates a receptacle of any suitable form for liquid paint, powder or other matter which it is desired to apply to a receiving surface, and 45 2 the cover thereof. To facilitate an easy and quick removal of the cover from or its application to the receptacle, the cover is fitted over the shouldered or beaded edge 3 of the receptacle and provided at different 50 points on one side edge thereof with lugs or hooks 4, which engage under the shoulder 3 and serve to hold such side of the cover to its seat on the receptacle. At the side of the cover opposed to the lugs 4, or substantially midway between such lugs, is pivoted

an angled latch-finger 5, which has a thumb engaging portion projecting outwardly from the edge of the cover and a portion lying along the cover edge and provided at its free end with lips 6, one of which engages over the cover edge and the other under the cover edge and shoulder 3 to cooperate with the lugs 4 to hold the cover to its seat on the receptacle. A spring 7 acts on the latch finger to normally retain it in locking engagement with the cover and shoulder. A tube 8 projects from near one side edge of the cover down into the receptacle to adjacent its bottom and is provided at its upper end without the cover with a restricted discharge nozzle 9, the throat of which inclines outwardly in the direction of the adjacent edge of the cover, as shown, or in the direction in which the spray is to be discharged.

Rising from the cover 2 in a diametrical line with the nozzle 9 are one or more standards 10, which provide bearings for an air-tube 11. This air-tube is disposed diametrically of the receptacle top and is held to the standards 10 for rotary adjustment relative thereto by cap-pieces 12, which hinge at one end to the standards, as at 13, and have their other ends secured thereto by thumbscrews 13', as shown, thus enabling the tube 11 to be securely clamped in adjusted position to the standards. The air-tube 11 has its discharge end provided with a restricted nozzle 14, which, when in operative position, is disposed to direct its air discharge across 90 the nozzle 9, to create a suction through such nozzle and its tube, as is well understood in the art.

The air-tube 11 has the end thereof which is opposed to its nozzle projected beyond the edge of the cover 2 and provided with an elbow 15, to which a handle 16 is threaded or otherwise suitably secured. This handle projects down at the side of the receptacle 1, preferably at right angles to the air-tube 100 13, and has a tube 17 projected axially therethrough with its inner end in connection through the elbow 15 with the bore or channel of the air-tube, and is adapted at its outer end for connection with a suitable 105 source of air supply under pressure. A valve 18 is located in the elbow 15 and is normally held seated to close the air passage by a spring 19 within the handle. The valve 18 has a stem 20 projecting without 110

the top of the elbow and provided with a thumb-piece 21 to facilitate a manipulation of the valve by the thumb of the hand grasping the handle 16. The thumb piece 5 of the latch-finger 5 is also disposed adjacent the handle 16, as shown.

To facilitate an agitating of the liquid within the receptacle 1 to prevent a settling of the heavy particles held in suspension 10 within the liquid, a branch tube 22 extends from the air-tube 11 down through the cover 2 and into the receptacle to near its bottom to permit a discharge of air from the tube 11 into the receptacle. A valve 23 controls 15 the passage of air through said branch tube, as is apparent. To permit a swinging of the tube 22 with the tube 11 when rotatably adjusted a transverse slot 24 is provided in the cover top for the tube 22 to project 20 through. This slot is of sufficient width to permit of a limited longitudinal adjustment of the tube 11 and attached parts.

In the use of my improved air-brush, the operator, having first adjusted the air- 25 nozzle 14 relative to the nozzle 9 to suit the form of spray desired, grasps the handle 16 with one hand and works the valve 18 with his thumb to control the air discharge from the nozzle 14 across the nozzle 9. If it is 30 desired to turn the handle relative to the receptacle to better facilitate the use of the device in cramped places or for spraying corners or the like, the screws 13' may be loosened to permit a turning of the tube 11 35 within the standards 10 to place the handle 16 at the desired angle relative to the receptacle and then tightened to lock the handle in such position. This feature is found to be quite important in the practical and efficient 40 operation of a device of this class. The mounting of the air-tube within the standards 10 as described, also permits an easy and quick relative adjustment of the nozzles 9 and 14 and a removal of the tube 45 from the standards to facilitate a cleaning of the parts.

I wish it understood that my invention is not limited to any particular construction or arrangement of the parts except in so far 50 as such limitations are specified in the claims.

Having thus described my invention, what I claim as new and desire to secure by Letters Patent, is,—

55 1. In an air brush, a receptacle, a tube extending therein and having a nozzle with-

out the receptacle, an air tube extending across the top of the receptacle and having one end terminating adjacent to said nozzle and its free end extending beyond the side 60 of the receptacle and thence downwardly at the side of the receptacle to form a handle, and means on the top of the receptacle for carrying said tube for adjustment transversely of the receptacle and for swinging 65 adjustment to permit a placing of the handle portion of the tube at different angles relative to the receptacle.

2. In an air brush, a receptacle, a tube extending therein and having a nozzle without the receptacle, standards on the top of said receptacle, an air tube mounted in said standards transversely of the top of the receptacle for rotary and longitudinal adjustment relative to the receptacle and having 70 one end terminating adjacent to said nozzle and its other end angled and extending downwardly along the side of the receptacle to form a handle, which is capable of swinging relative to the receptacle when said tube is rotated in said standards, means for clamping the tube in adjusted position and an air valve located within said handle and having its stem projecting axially of the handle through the upper end thereof and 75 terminating in position to be operated by the thumb of a hand grasping the handle.

3. In an air-brush, a receptacle, spraying means carried by the receptacle and having an air-tube extending transversely of one 80 end of the receptacle and having one end projected beyond the side of the receptacle and angled to extend along the side of the receptacle in spaced relation thereto to form a handle, said angled portion being in communication with the source of fluid under pressure, a valve located within the handle portion of said tube and having a stem projecting axially therefrom without the angled portion of the tube and at substantially 85 right-angles to the portion of the tube projecting across the receptacle, and a thumb piece carried by the valve stem without the tube in position to be pressed by the thumb of a hand grasping the handle.

105 In testimony whereof, I have hereunto signed my name to this specification in the presence of two subscribing witnesses.

NIELS MARTIN HANSEN.
